(57) **ABSTRACT**

A crimping tool uses a die set with a single point indenter profile to allow of a wide range of electrical connectors and conductors without changing die sets and/or crimping tools. This avoids the need to purchase a separate crimping tool. A die set with an indenter feature in two configurations encompasses the required range of conductors in existing crimping tools, consisting of two pyramid indenter dies and one common wedge die. One advantage of this invention is it allows the strength and versatility of a die set with a single-point indenter without the purchase of a separate crimping tool. The dies of this invention do not require switching out for different sized lugs, thus reducing misplacement and loss. The die halves replace numerous standard U-dies, making the dies of this invention more appealing while offer enhanced pullout strength of connections resulting from this invention.

CRIMPING ASSEMBLY, TOOL AND DIE DESIGN

This claims the benefit of U.S. Provisional Patent Application Ser. No. 63/044,415, filed Jun. 26, 2020 and hereby incorporated by reference in its entirety.

BACKGROUND OF THE INVENTION

This invention relates generally to a crimping assembly. More particularly, this invention relates to a crimp tool and die set useful for a wide variety of crimping applications and methods of using the same.

Many portable power tools are handheld tools that have electric motors to drive a working head used to perform various tasks, such as crimping, drilling, shaping, fastening, grinding, polishing, heating, etc. Some portable tools incorporate a hydraulic pump to enable the working head to apply a relatively large amount of force or pressure for a particular task. Such tools may operate with a hydraulic pump actuated by a battery powered electric motor. Battery powered hydraulic power tools are employed in numerous applications to provide an operator with a desired flexibility and mechanical advantage.

One common use of such tools is for making crimping connections, such as crimping large power connectors or lugs onto large conductors. This application may require added force to crimp such large conductors, e.g., #8 conductors and larger, to suitable connectors. Such battery powered hydraulic power tools often come with dies to perform the crimping operation.

Hand-operated or motor-driven hydraulic tools are often employed for such joining procedures. These tools may be provided with an excess pressure valve which limits the oil pressure, and thus the compressive force of the moving part against the workpiece to be pressed, to a maximum value. It is important to ensure a well-made joint between an electrical connector, such as a cable eye, and an electrical conductor. A prescribed minimum compressive force is desired to achieve such a connection. After release of the crimping tool, or rather the moving part thereof, it is returned to the initial position, i.e. the open position of the crimping tool.

Crimping tools using interchangeable accessory dies are known in the art. As will be appreciated by one of ordinary skill in the art, crimp die sets are used in various fields for various purposes. One particularly applicable field involves the crimping of connectors onto multi-service conductors as described above.

For these types of environments, particularized crimp die sets and methods have been developed. For example, when installing electrical connectors to conductor ground wires, it is particularly imperative that the materials stay connected even under stress or otherwise the connection is lost. To this end, Underwriter's Laboratories (UL) has promulgated standards for electrical connectors that specify a minimum "pull off" value. As will be appreciated, the pull off value is the amount of stress (pounds) that is required to pull the connector off of the conductor. By requiring a minimum pull off value, UL-approved products can help assure that wires and the like stay attached to the metal connectors through the range of stresses that may be encountered in the applicable environment, thereby maintaining the protection against ground faults and loss of electrical connection.

Originally, die taking tools such as crimping tools were created to allow the connector or lug to be matched with the exact die necessary to crimp the particular lug. However,

some existing crimping tools such as 12-ton crimping tools cannot crimp a 1000 kcmil lug due to physical constraints which do not allow the 1000 kcmil lugs to fit between the jaws of a 12-ton tool when the dies are in place. One tool solution requires a separate tool to be purchased and utilized for the needed space between the dies installed in the tool. This option requires a high inventory of dies and tools which is expensive and inefficient in the field.

One option would be to procure a separate 15T tool with sufficient opening between the jaws, and then purchase adapters to fit the u-dies or procure a single point indenter tool capable of crimping a 1000 kcmil Lug. The inventory of crimping tools and necessary dies makes such a solution impractical.

SUMMARY OF THE INVENTION

These and other shortcomings in the prior art have been addressed by embodiments of this invention which may include a crimping assembly, crimping tool, die sets and associated methods.

In one embodiment, this invention is a die set with a single point indenter profile for fitment into a 12T U-die taking tool, allowing crimping of a 1000 kcmil lug with the current tool format. This avoids the need to purchase a separate crimping tool. As is known by one of ordinary skill in the art, kcmil or circular mil is a unit of area, equal to the area of a circle with a diameter of one mil (one thousandth of an inch). It is a unit intended for referring to the area of a wire with a circular cross section. As the area in circular mils can be calculated without reference to π , the unit makes conversion between cross section and diameter of a wire considerably easier.

In Canada and the United States, the National Electrical Code (NEC) uses the circular mil to define wire sizes larger than 0000 AWG. In many NEC publications and uses, large wires may be expressed in thousands of circular mils, which may be abbreviated as Kcmil. For example, one common wire size used in the NEC has a cross-section of 250,000 circular mils, written as 250 kcmil, which is the first size larger than 0000 AWG used within the NEC.

In one embodiment, this invention includes a die set with an indenter feature in two configurations to encompass the required range of conductors in existing crimping tools, consisting of two pyramid indenter dies and one common wedge die.

One advantage of this invention is it allows the strength and versatility of a die set with a single-point indenter without the purchase of a separate crimping tool. The dies of this invention do not require switching out for different sized lugs, thus reducing misplacement and loss. Three die halves replace 20 standard U-dies, making the dies of this invention more appealing to contractors.

Pullout strength of connections resulting from this invention increase by 33% with one crimp, and 15% with 2 crimps over traditional U-dies.

Embodiments of this invention allow for crimping of 1000 kcmil lugs and splices in a 12 ton hand or battery-operated crimping tool.

Embodiments of this invention allow a U-die taking crimping tool to have greater range, 1000 kcmil to #8 than current U-dies allow.

Embodiments of this invention allow versatility of U-die taking crimping tool to become a single-point indenter tool preferred by many users.

BRIEF DESCRIPTION OF THE DRAWINGS

The above-mentioned and other features and advantages of this invention, and the manner of attaining them, will

become more apparent and the invention itself will be better understood by reference to the following description of embodiments of the invention taken in conjunction with the accompanying drawings, wherein:

FIG. 1 is a perspective view of one embodiment of a die-set according to this invention;

FIG. 1A is a perspective view of an exemplary crimping tool into which the die-set of FIG. 1 may be used;

FIG. 2 is a side elevational view of the die-set of FIG. 1 installed into the jaws of the crimping tool of FIG. 1A;

FIG. 3A is a cross-sectional view of the arrangement of FIG. 2 with a conductor and lug positioned in the jaws of the crimping tool;

FIG. 3B is a view similar to FIG. 3A with the jaws and die-set crimping the conductor and lug;

FIG. 3C is a view similar to FIGS. 3A-3B with the crimped conductor and lug being removed from the jaws;

FIG. 4 is a perspective view of a second embodiment of a die-set according to this invention;

FIG. 5 is a side elevational view of the die-set of FIG. 4 installed into the jaws of the crimping tool;

FIG. 6A is a cross-sectional view of the arrangement of FIG. 5 with a conductor and lug positioned in the jaws of the crimping tool;

FIG. 6B is a view similar to FIG. 6A with the jaws and die-set crimping the conductor and lug;

FIG. 6C is a view similar to FIGS. 6A-6B with the crimped conductor and lug being removed from the jaws;

FIG. 7 is a perspective view of a third embodiment of a die-set according to this invention;

FIG. 8 is a side elevational view of the die-set of FIG. 7 installed into the jaws of the crimping tool;

FIG. 9A is a cross-sectional view of the arrangement of FIG. 8 with a conductor and lug positioned in the jaws of the crimping tool;

FIG. 9B is a view similar to FIG. 9A with the jaws and die-set crimping the conductor and lug;

FIG. 9C is a view similar to FIGS. 9A-9B with the crimped conductor and lug being removed from the jaws;

FIG. 10 is a perspective view of a fourth embodiment of a die-set according to this invention;

FIG. 11 is a side elevational view of the die-set of FIG. 10 installed into the jaws of the crimping tool;

FIG. 12A is a cross-sectional view of the arrangement of FIG. 11 with a conductor and lug positioned in the jaws of the crimping tool;

FIG. 12B is a view similar to FIG. 12A with the jaws and die-set crimping the conductor and lug;

FIG. 12C is a view similar to FIGS. 12A-12B with the crimped conductor and lug being removed from the jaws;

FIG. 13 is a perspective view of a fifth embodiment of a die-set according to this invention;

FIG. 14 is a side elevational view of the die-set of FIG. 13 installed into the jaws of the crimping tool;

FIG. 15A is a cross-sectional view of the arrangement of FIG. 14 with a conductor and lug positioned in the jaws of the crimping tool;

FIG. 15B is a view similar to FIG. 15A with the jaws and die-set crimping the conductor and lug; and

FIG. 15C is a view similar to FIGS. 15A-15B with the crimped conductor and lug being removed from the jaws.

shown in FIG. 1A, a conventional crimping tool 10 includes a housing 12, a working head 14, die release buttons 16, a battery 18, a trigger 20, and a ring 21. The housing 12 forms a handle 28. The battery 18 is removably connected to the bottom of the handle 28. The tool 10 can also include additional or alternative components. The housing 12 forms a ram hydraulic drive conduit system. The working head 14 may include a frame section 22 and a ram 24. The frame section 22 is stationarily connected to the front end of the housing 12, but could be rotatable. The ram 24 is movably connected to the frame section 22. The frame section 22 and the ram 24 are adapted to removably receive crimping dies 30 at a conductor receiving area 26. The crimping tool 10 shown and described herein is exemplary and this invention is not limited to any specific crimping tool. One crimping tool which may be used with this invention is model ILBC-12-LIO from Ilseco Corporation.

The ram 24 moves forward and backward axially as indicated by arrow A. The ram hydraulic drive conduit system is connected between a pump and the rear end of the ram 24. Hydraulic fluid pumped by the pump against the rear end of the ram 24 causes the ram 24 to move forward. A spring (not shown) returns the ram 24 to its rearward home position when hydraulic fluid pressure is released. The ram 24 moves between its rear position (FIG. 2) and its forward position (FIG. 3B).

Referring to FIGS. 1-2, one embodiment of a die set 30 for use in the crimping tool 10 is shown. The die set 30 and crimping tool 10 may be used to crimp an electrical connector such as a lug 32 shown in cross-section in FIG. 2 onto multiple wires 34 of a conductor 36 for electrical connection between the lug 32 and conductor 36. The die set 30 may have an upper indenter die 30a and a lower common die 30b. The upper die 30a may be mounted to the ram 24 of the crimping tool 10 according to various embodiments of this invention; however, since the crimping tool 10 can accept either die 30a, 30b in either location, the labels of upper die and lower die are for convenience in identification purposes.

The receiving 26 area of the crimping tool 10 has a pair of jaws 38 opposing one another. Each die 30 is removably mounted into one of the jaws 38. One jaw 38b is found on the frame 22 of the head 14 of the crimping tool 10 and one jaw 38a is found on the ram 24 of the tool 10. Each jaw 38 has a pair of opposed rails 40, one of which is oriented downwardly and one of which is oriented upwardly as shown in FIG. 2. Each jaw 38 has a curved or arcuate concave surface 42 extending between the associated rails 40 therefrom.

An outer mating surface 44 of each die 30 is a generally curved or arcuate convex surface which is sized and configured to mate with the concave surface 42 of the jaws 38 when the die 30 is mated thereto. Each die 30 has a pair of grooves 46, one at each circumferential extent of the concave surface 44. One of the grooves of each die 30 is an upper groove 46a and the other groove of each die is a lower groove 46b. As seen in FIG. 2, the upper rail 40a of each jaw 38 is seated within the upper groove 46a and the lower rail 40b of that jaw 38 is seated within the lower groove 46b of the associated die 30 when the die 30 is mated with the jaw 38. The release button 16 may be depressed to release the die 30 from the associated jaw 38 as needed.

Each die 30 has a working surface 48 which confronts the working surface 48 of the opposing die 30 of the die set when the dies 30 are mounted in the crimping tool 10. According to various embodiments of this invention, the lower die 30b as a generally V-shaped working surface 48b when the die is viewed from the longitudinal end as in FIG.

DETAILED DESCRIPTION OF THE INVENTION

A crimping tool and crimping die set commonly used in installing electrical connectors is depicted in FIGS. 1-1A. As

2 or a cross-sectional view taken perpendicular to the grooves 46 of the die 30. The working surface 48b of the lower die 30b has a pair of generally planar and rectangular surfaces 50 joined together along a common longitudinal edge by a vertex 52 of the V-shape as seen in FIG. 2. The vertex 52 may have a rounded or other configuration according to various embodiments of this invention.

The working surface 48a of the upper die 30a according to various embodiments of this invention includes an indenting member 54, an example of which is seen in FIG. 1. The indenting member 54 of FIG. 1 is a generally pyramidal shaped member having four trapezoidal-shaped sides 56 which merge together at a square shaped, generally planar apex 58. The indenting member 54 projects from a generally planar, rectangular shaped base 60 of the working surface 48a of the upper die. The base 60 joins the upper and lower grooves 46 of the upper die 30a together in the embodiment of FIG. 1. The indenting member 54 is positioned generally equal distances from the upper and lower grooves 30 and laterally between the ends of the working surface 48. The indenting member 54 of various embodiments of this invention has two planes or axes of symmetry A1 and A2 as shown in FIG. 1 and other drawings.

As shown in the drawings, various embodiments of this invention form a single point indentation 62 in the lug or connector 32 and the conductor 36 positioned therein. The single point indentation 62 provides a crimp of sufficient strength and versatility to facilitate removal of the crimped lug or connector 32 and conductor 36 from the crimping tool 10. The die sets 30 of this invention allow for removal of the crimped connector 32 and conductor 36 from 12 ton hand or battery operated tools 10. Single point indentations 62 are preferred by many in the industry and with the components of this invention, the distance within receiving area 26 allows for removal of the crimped members with standard tools 10. 1000 kcmil to #8 connectors 32 may be effectively crimped in such tools 10 and easily removed therefrom.

FIGS. 3A-3C are sequential views of the lug 32 and conductor 36 being crimped by the die set 30 of FIG. 1 and the crimping tool 10 and then removed from the receiving area 26 between the dies 30 in the crimping tool 10. The arrangements of FIGS. 2 and 3A are similar and represent the maximum extent of the receiving area 26 with the ram 24 and upper die 30a mounted in the associated jaw 38 at the home position fully retracted from the lower die 30b and associated jaw 38 of the crimping tool 10. In FIG. 3B, the position of the upper die 30a relative to the lower die 30b has decreased with the ram 24 of the crimping tool 10 being actuated by a user depressing the trigger 20. The relative movement of the dies 30 toward each other, as indicated by arrows B in FIG. 3A in one embodiment, crimps the lug 32 and conductor 36 therebetween as seen in FIG. 3B. The portion of the lug 32 and wires 34 of the conductor 36 adjacent thereto are deformed into a generally V-shaped configuration similar to the working surface 48b of the lower die 30b. Similarly, the portion of the lug 32 confronting the upper die 30a and the adjacent wires 34 of the conductor 36 are deformed by the indenting member 54 and base 60 of the working surface 48a of the upper die 30a. The indenting member 54 forms an indentation 62 in the lug 32 and adjacent wires 34 of the conductor 36.

After the ram 24 and upper die 30a mounted thereto has completed the crimping action and/or traveled to the furthest extent of the ram 24, the ram 24 is retraced toward home position to unseat the crimped surfaces of the lug 32 from the respective working surfaces 48 of the die set 30. This allows for removal of the crimped lug and conductor from

the receiving area 26 of the crimping tool 10, such as in the direction of arrow C as seen in FIG. 3C.

Advantageously, the configuration of the dies 30 and associated working surfaces 48 of the die set 30 allows for a secure crimp of a variety of lug 32 and conductor 36 sizes, including large sizes which would otherwise require a different tool and/or die set for such larger sizes thereby increasing the required inventory of dies and/or crimping tools to securely crimp larger diameter lugs and conductors.

A second embodiment of a die set 30 according to this invention is shown in FIG. 4 with the die set 30 mated with the crimping tool 10 shown in FIG. 5. Elements of the die set 30, crimping tool 10, lug 32 and conductor 36 similar to those of the earlier embodiment are identified by similar reference numerals. The lower die 30b of the die set 30 of FIG. 4 is similar to or the same as the lower die 30b of the die set 30 of FIG. 1. The upper die 30a of FIG. 4 differs from the upper die of FIG. 1 by the addition of added indenting members in the form of a pair of rims 54a, 54b each projecting forwardly from the base 60 at a juncture between the base 60 and the associated groove 46 of the upper die 30a. The rims 54a, 54b form recesses 64a, 64b in the lug 32 and adjacent wires 34 of the conductor 36 as shown in FIGS. 6B and 6C. The height of each rim 54a, 54b is less than that of the pyramidal shaped indenting member 54 in the embodiment of FIGS. 4-6C, although other configurations and shapes are within the scope of this invention.

A third embodiment of a die set 30 according to this invention is shown in FIG. 7 with the die set 30 mated with the crimping tool 10 shown in FIG. 8. Elements of the die set 30, crimping tool 10, lug 32 and conductor 36 similar to those of the earlier embodiments are identified by similar reference numerals. The lower die 30b of the die set 30 of FIG. 4 is similar to or the same as the lower die 30b of the die set 30 of FIGS. 1 and 4. The upper die 30a of FIG. 7 differs from the upper dies 30a of FIGS. 1 and 4 by the shape of the indenting member 54 on the working surface 48a. The indenting member 54 of the upper die 30a of the die set 30 of FIG. 7 is a saddle shaped member with a pair of generally oval shaped pockets 66 spaced on either side of a laterally oriented ridge 68. Each of the oval shaped pockets 66 is adjacent to one of the grooves 46 of the upper die 30a. The indenting member 54 of the upper die 30a of FIG. 7 forms a central indentation 62 in the lug 32 bordered on the upper and lower portions of the lug 32 by rounded protrusions 70 as shown in FIG. 9C.

A fourth and fifth embodiment of a die set 30 according to this invention is shown in FIGS. 10 thru 15C with the die set 30 mated with the crimping tool 10 shown in FIGS. 11 and 14. Elements of the die set 30, crimping tool 10, lug 32 and conductor 36 similar to those of the earlier embodiments are identified by similar reference numerals. The lower die 30b of the die set 30 of FIG. 4 is similar to or the same as the lower die 30b of the die set 30 of FIGS. 1 and 4. The upper dies 30a of FIGS. 10 and 13 differs from the upper dies 30a of FIGS. 1 and 4 by the shape of the indenting member 54 on the working surface 48a as shown in FIGS. 10-15C. The indenting member 54 of the embodiments shown in FIGS. 10-15C are similar to each other with the member 54 of FIGS. 10-12C being less pronounced than the member 54 in FIGS. 13-15C. Each of these embodiments of the indenting member 54 has a pair of shaped pockets 66 spaced on either side of the protruding ridge 68. The outermost face of the ridge 68 of the embodiment in FIGS. 10-12C is generally square while the outermost face of the ridge 68 of the embodiment of FIGS. 13-15C is rectangular.

The various embodiments of the die sets 30 according to this invention each offer the secure crimp of a variety of lug 32 and conductor 36 sizes, including large sizes which would otherwise require a different tool and/or die set for such larger sizes thereby increasing the required inventory of dies and/or crimping tools to securely crimp larger diameter lugs and conductors.

From the above disclosure of the general principles of this invention and the preceding detailed description of at least one embodiment, those skilled in the art will readily comprehend the various modifications to which this invention is susceptible. Therefore, we desire to be limited only by the scope of the following claims and equivalents thereof.

We claim:

1. A crimping assembly for crimping a connector onto a conductor, the crimping assembly comprising:

a crimping tool having a frame section and a ram;
a first die and a second die, each of which is adapted to be removably coupled to one of the frame section and the ram such that when the conductor and connector are positioned between the first and second dies the crimping tool is operable to crimp the connector onto the conductor;

each of the first and second dies having an outer mating surface to removably mate with one of the frame section and the ram;

wherein each of the first and second dies having a working surface that confronts one of the connector and the conductor when positioned in the crimping tool;

the working surface of the first die having an indenting member projecting therefrom to form an indentation in the connector when crimped to the conductor by the crimping tool;

the indenting member having a plurality of non-planar faces, including two non-planar faces that each include a pocket.

2. The crimping assembly of claim 1 wherein the indenting member forms a single point indentation in the connector to facilitate removal of the conductor and the connector crimped thereon from the crimping tool.

3. The crimping assembly of claim 2 wherein the indenting member has a pyramidal shape.

4. The crimping assembly of claim 1 wherein the indenting member has two planes of symmetry oriented perpendicularly to each other.

5. The crimping assembly of claim 1 wherein the working surface of the first die further comprises:

a pair of spaced rims with the indenting member positioned therebetween.

6. The crimping assembly of claim 1 wherein the indenting member has a plurality of planar faces.

7. The crimping assembly of claim 1 wherein one of the plurality of non-planar faces is smoothly continuous and extends from one lateral end of the working surface to an opposite lateral end of the working surface.

8. The crimping assembly of claim 1 wherein the two of the plurality of non-planar faces are mirror images of each other.

9. The crimping assembly of claim 1 wherein the outer mating surfaces of each of the first and second dies are compatible with both the frame section and the ram.

10. The crimping assembly of claim 1 wherein the crimping assembly is sized to receive the connector that is of a size between 1000 kcmil to #8, and the crimping tool has a 12 ton capacity.

11. A die set for use in a crimping tool for crimping a connector onto a conductor, the die set comprising:

a first die and a second die, each of which is adapted to be removably coupled to one of a frame section and a ram of the crimping tool such that when the conductor and connector are positioned between the first and second dies the crimping tool is operable to crimp the connector onto the conductor;

each of the first and second dies having an outer mating surface to removably mate with one of the frame section and the ram;

each of the first and second dies having a working surface which confronts one of the connector and the conductor when positioned in the crimping tool; and

the working surface of the first die having an indenting member projecting therefrom to form an indentation in the connector when crimped to the conductor by the crimping tool, the indenting member having a plurality of non-planar faces, including two non-planar faces that each include a pocket.

12. The die set of claim 11 wherein the indenting member forms a single point indentation in the connector to facilitate removal of the conductor and the connector crimped thereon from the crimping tool.

13. The die set of claim 11 wherein the indenting member has two planes of symmetry oriented perpendicularly to each other.

14. The die set of claim 13 wherein the indenting member has a pyramidal shape.

15. The die set of claim 14, wherein the indenting member further includes a ridge, the pockets being disposed on opposing sides of the ridge; and

wherein the ridge is one or more of square or rectangular.

16. The die set of claim 11 wherein the working surface of the first die further comprises:

a pair of spaced rims with the indenting member positioned therebetween.

17. The die set of claim 11 wherein one of the plurality of non-planar faces is smoothly continuous and extends from one lateral end of the working surface to an opposite lateral end of the working surface.

18. The die set of claim 11 wherein the two non-planar faces are mirror images of each other.

19. The die set of claim 11 wherein the working surface of the second die has a pair of planar faces.

20. The die set of claim 19 wherein the pair of planar faces are oriented perpendicularly relative to each other.

21. The die set of claim 11 wherein the outer mating surfaces of each of the first and second dies are compatible with both the frame section and the ram.

22. The die set of claim 11, wherein the indenting member further includes a ridge, the pockets being disposed on opposing sides of the ridge.

23. A method of using a die set with a crimping tool for crimping a connector onto a conductor, the method comprising:

coupling a first die to a crimping tool by removably mating a first outer mating surface of the first die with one of a ram or a frame section of the crimping tool; coupling a second die to the crimping tool by removably mating a second outer mating surface of the second die to the outer of the ram or the frame section;

positioning the conductor and the connector between the first and second dies, so that a working surface of each of the first and second dies confronts the connector or the conductor; and

operating the crimping tool to crimp the connector onto the conductor by forming an indentation in the connector with a plurality of non-planar faces of an indent-

ing member that projects from the working surface of the first die, the plurality of non-planar faces of the indenting member including two non-planar faces that each include a pocket.

24. The method of claim **23**, wherein forming the indentation in the connector with the first die includes forming a single point indentation in the connector with the indenting member. 5

25. The method of claim **23**, wherein the indenting member further includes a ridge, the pockets being disposed 10 on opposing sides of the ridge.

26. The method of claim **25**, wherein the plurality of non-planar faces includes a smoothly continuous non-planar face that extends at least partially from one lateral end of the working surface to an opposite lateral end of the working 15 surface.

27. The method of claim **25**, wherein an outermost face of the ridge is one or more of square or rectangular.
